A. W. MATTHEWS

MACHINE FOR OPERATING ON HEELS

Filed Oct. 17, 1925

Fig.1.

UNITED STATES PATENT OFFICE.

ALGERNON W. MATTHEWS, OF HAVERHILL, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON HEELS.

Application filed October 17, 1925. Serial No. 63,148.

This invention relates to machines for operating upon the heels of boots and shoes and is illustrated as embodied in a machine for trimming the breast portions of heels, 5 for example Louis heels. The invention is illustrated as embodied in a machine of the type disclosed in United States Letters Patent No. 1,426,354, granted August 22, 1922, on application of D. W. Bunker.

10 Machines of this type comprise a rotary cutter and a work support against which the tread face of the shoe is held and between which and the cutter there is relative movement to carry the heel across the acting face of the cutter. In order that the proper amount may be removed from the heel breast it is necessary to locate the heel accurately longitudinally, and when, according to the 15 usual practice, a gage is provided on the shoe support to engage the breast face of the heel, the gage must have very slight extent heightwise of the heel in order not to interfere with the action of the cutter upon the heel breast. On the other hand, 20 unless a gage of substantial height is provided, the proper location of the heel is difficult to obtain and maintain.

25 Objects of this invention are to provide an adequate gage for locating the heel longitudinally which will not interfere with the action of the cutter upon the heel.

30 Features of the invention consist in an organization comprising a rotary cutter and a shoe support or carrier, the cutter and carrier being arranged for relative movement to present the shoe to the cutter, and a gage against which the breast face of the heel may be held prior to said relative movement of the cutter and carrier but which 35 does not remain in contact with the heel when the latter and the cutter are brought together. As illustrated, the shoe carrier is arranged for movement relatively to the cutter and the gage, and is normally below the 40 cutter, the gage being arranged to engage the heel when the carrier is in its lowest position and to remain stationary during the movement of the carrier toward the cutter so that the heel is carried away from the 45 gage and across the field of action of the cutter which therefore acts upon the heel without any possible chance of interference 50 with its action by the gage.

These and other features of the invention

will appear more fully from the following 55 detailed description when read in connection with the accompanying drawing and will be pointed out in the appended claims.

In the drawing,

Fig. 1 is a side elevation of a machine 60 embodying the present invention,

Fig. 2 is a plan view of the shoe-positioning devices, and

Fig. 3 is a perspective view, partly in 65 section, of the gage for locating the breast edge of the heel.

Referring to Fig. 1 of the drawings, the numeral 2 indicates the column of the machine on the upper portion of which is a head 4 having bearings for a cutter shaft 10 70 arranged to be driven from a suitable source of power. On one end of the shaft 10 is a cutter-head 14 having two fly cutters 16 the cutting portions of which are shaped to give the proper contour to the breast edge of a Louis heel. The shoe-supporting and carrying mechanism is mounted on a long, downwardly extending bracket 20 which, near its upper end, has a dovetailed portion 22 arranged to slide in a guideway formed in a projection 24 from the column 2 and extending parallel to the shaft 10. A hand-wheel 26 and a screw 28 are provided for adjusting the slide 22 in its guideway, the parts being maintained in position by a suitably 75 arranged screw having a hand-wheel 32 by 80 which it can be turned.

Pivoted at 34 to the lower end of the bracket 20 is a clamping member 36 through 85 which a shaft 38 extends, the clamping member being tightened on the shaft by a bolt 40. The shaft 38 extends upwardly to a point beneath the cutter-head 14 where it is reduced to form a heel-locating gage. As shown in Figs. 2 and 3, the reduction 90 of the shaft consists in cutting away about three-fourths of its cross-section, leaving a segmental portion 42 one flat face 44 of which is utilized as a gage for locating the heel longitudinally by engagement with its breast face. A square, hollow post 46 is fitted to slide on the upper portion of the shaft 38 and is guided by opposite flat faces 95 formed on a projection 48 extending forwardly from the bracket 20. A member 50 which carries means for locating the shoe by engagement with its tread face is secured by a clamping bolt 52 to the upper 100 105

end of the post 46 and is held in proper relation to the gage 42 by a key 51 which engages a groove 53 in the shaft 38, as shown in Fig. 3. The member 50 has an arm 54 (Fig. 2) carrying an upright member 56 for engaging the tread face of the forepart and has also a flat portion 58 against which the tread face of the heel is placed. From Fig. 2 it will be seen that the surface of the portion 58 which the tread face of the heel engages is at right angles to the surface 44 of the gage 42 against which the breast face of the toplift is positioned, and that the surface 58 is arranged far enough back of the front edge of the surface 44 so that an adequate portion of the gaging surface 44 is exposed.

In order to hold a shoe which has been located by the positioning means 56, 58 and 42, a pair of jaws 60, 62 is provided. These jaws are pivoted by pins 64 to the member 50 and have interengaging teeth so that when one jaw is moved the other will be moved equally and oppositely. The amount of initial separation of the jaws is determined by a screw 68 which is threaded through an arm 70 of the jaw 62 and engages a projection 72 on the jaw 60.

To operate the jaws, the upper end of a push rod 80 is connected at 82 with the arm 70 of the jaw 62 and the lower end is pivoted at 84 to a lever 86 fulcrumed at 88 to a bracket 90 secured to the floor. A treadle member 92 is pivoted at 94 and has, at its outer end, a pin and slot connection 96 with the lever 86. Consequently, when the outer end of the treadle 92 is pressed upon, the lever 86 will be operated to push upwardly on the rod 80 first to close the jaws 60, 62 upon the heel. Further movement of the treadle will cause the jaws and the tread face engaging members to be lifted with the post 46 to present the breast face of the heel to the action of the cutter 16. The member 50 is shaped to embrace the rear part of the shoe and to form a guard for the operator's hand which holds the rear portion of the shoe.

The organization of the illustrated machine is such that at the option of the operator the machine may be used to breast transversely straight heels or transversely convex heels. A roll 102 mounted on the post 46 may be set to engage a straight, vertical face formed on the front edge of a track 104. The roll 102 is held against the track 104 during upward movement of the post 46 by a spring 106 arranged between the bracket 20 and an adjustable nut 108 on a rod 110 which passes through the bracket and is pivoted to a collar 112 embracing the shaft 38. When the roll 102 is thus located on the track 104, the heel is given a transversely straight breast.

Arranged alongside the plate 104 is a sec-

ond plate 114 having a cam surface on its front edge with which the roll 102 may, at the option of the operator, be set to engage. As shown in Fig. 2, the roll is mounted on a shaft 116 to which a sleeve 118 is pinned. The sleeve 118 slides in a bore formed in a boss 120 and through which the shaft 116 passes. Between the sleeve 118 and the bottom of the bore is a spring 122. On the outer end of the shaft 116 is a thumb-head 124 which has a projection 126 arranged to enter a recess in the boss 120. As shown in Fig. 2, the roll 102 engages the cam surface 114 and, during upward movement of the shoe, the shoe-locating and carrying parts will be moved first away from the cutter and then toward it, causing the cutter to impart a transverse convexity to the breast face of the heel. If it is desired to use the machine for imparting a transversely straight breast to the heel, the shoe carrier will be moved outward slightly against the tension of the spring 106 and the thumb-head 124 will be pulled outwardly and given a partial rotation so that the projection 126 will rest against the outer surface of the boss 120. The roll 102 will then be located opposite the straight edge of the plate 114 and the shoe will be guided in a straight, vertical path. The plates 104, 114 are secured by screws 130 which pass through slots in a standard 132 extending upwardly from the bracket 120 and are threaded into the plates. A screw 134 is threaded into the upper end of the standard 132 and has a flange 136 which engages a horizontal slot in the plate 104. By loosening the screw 130 and turning the screw 134 the plates 104, 114 may be adjusted vertically. This enables the cam plate 114 to be so adjusted that the transverse convexity of the heel breast will be properly located transversely of the heel.

In order that the shoe carrier may be adjusted toward and from the cutter so that the knife will clear the shank surface of the shoe, the roll 102 is arranged for adjustment at right angles to the shaft 10. As shown in Fig. 2, the boss 120 is formed on a slide 138 which can be adjusted inwardly and outwardly by turning a thumb-head 144, and is held in adjusted position by a screw 146.

As shown in Fig. 1, mechanism is provided for preventing the cutter from chipping the lower edge of the heel breast. This comprises a member 162 loose on the shaft 38 between which and a collar 158 fixed to the shaft is a spring 164. Secured to the member 162 is a rod 166 passing through an ear 168 on the post 46 and having stop collars 170, 172, respectively, above and below the ear 168. During the upward movement of the shoe and when the action of the cutter on the heel is about to be finished, the ear 168 will engage the collar 170, thus bringing the spring 164 into action to retard the later

portion of the upward movement of the shoe and cause the cutter to make a clean cut on the lower edge of the heel breast.

6 A counter-balancing spring 174 may be connected between the frame and the shoe carrier to sustain at least part of the weight of the parts moved by the treadle and thus assist the operator in operating the machine.

10 Having thus described my invention, what I claim as new and desire to secure by Letters Patent of the United States is:

1. In a machine of the class described, the combination of a cutter, a shoe carrier, 15 means for moving the cutter and shoe carrier relatively to cause the cutter to treat the heel, and a stationary gage against which the shoe is positioned prior to said relative movement to determine the position of the shoe relatively to the carrier.

2. In a machine of the class described, the combination of a rotary cutter, a shoe carrier movable across the acting face of the cutter, and a stationary gage for positioning the shoe relatively to the carrier prior to movement of the carrier across the cutter.

3. In a machine of the class described, the combination of a rotary cutter, a rest for the tread face of the heel, means for moving the rest and shoe across the cutter, and means for engaging the breast face of the heel by which the heel is located longitudinally and which does not partake of the movement of the tread rest.

35 4. In a machine of the class described, the combination of a shoe gage for locating the shoe, a shoe holder movable relatively to the gage, and a rotary cutter to which the holder presents the shoe after it leaves the gage.

40 5. In a machine of the class described, the combination of a rotary cutter, a tread rest against which the tread face of the heel of a shoe is held by the hand of the operator, a breast gage against which the breast edge of the top-lift is held to locate the heel longitudinally, and means for relatively moving the cutter and the rest to cause operation of the cutter upon the breast of the heel and for relatively moving the gage and the shoe so that the gage will not interfere with the action of the cutter on the heel breast.

55 6. In a machine of the class described, the combination of a rotary cutter, a tread rest to receive the tread face of the heel of a shoe, means adjacent to the tread rest to engage the breast edge of the toplift of the heel, and means for moving the tread rest and said means relatively and to carry the heel past the cutter.

60 7. In a machine of the class described, the combination of a rotary cutter, a tread rest to receive the tread face of the heel of a shoe, a stationary gage adjacent to which the tread rest stands initially and by which

the heel is located longitudinally, and means for moving the tread rest to transfer the shoe from said gage to the cutter.

8. In a machine of the class described, the combination of a rotary cutter, a pair of 70 jaws movable relatively to the cutter, a gage for positioning the shoe relatively to the jaws, and means for closing the jaws and moving them relatively to the cutter and away from said gage to cause the cutter to 75 act on the heel without interference with the gage.

9. In a machine of the class described, the combination of a rotary cutter, a pair of 80 jaws movable relatively to the cutter, a gage 80 for locating the shoe relatively to the jaws, and means for closing the jaws and moving them relatively to the cutter and away from the gage to cause the cutter to act on the heel and to avoid interference of the gage 85 with such action.

10. In a machine of the class described, the combination of a rotary cutter, a rest for the tread face of the heel, a stationary gage for the breast edge of the heel, means for relatively moving the cutter and the rest to cause operation of the cutter upon the breast face of the heel, and means operated by said moving means for holding the shoe upon the rest.

95 11. In a machine of the class described, the combination of a rotary cutter, a rest for the tread face of the heel movable relatively to the cutter to cause operation of the cutter upon the breast of the heel, a pair of jaws 100 on the rest for engaging the heel of the shoe, a gage for locating the shoe heel relatively to the jaws, and means for operating on said rest and jaws for causing the jaws to hold the heel and to move the heel away from 105 the gage and across the cutter.

12. In a machine of the class described, the combination of a rotary cutter, a rest for the tread face of a heel, manually operated means for moving the shoe across the cutter 110 to cause the cutter to breast the heel, holding means arranged to close against the sides of the heel, a stationary gage for locating the heel relatively to the holding means, and means operated by said manually operated 115 means for closing the holding means.

13. In a machine of the class described, the combination of a cutter, a rest to engage the tread face of a heel to be acted upon by said cutter, means mounted independently of the 120 rest for engaging the breast face of the heel while in contact with said rest to locate the heel longitudinally, and means for moving the rest and shoe away from said breast-engaging means and across the cutter.

125 14. In a machine of the class described, the combination of a tool, a shaft, the end portion of the shaft forming a gage for positioning the work, a carrier movable toward the tool, and means on said carrier for grasp-

ing the work positioned against the gage, said carrier being movable on the shaft to present the work to the tool.

15. In a machine of the class described, the combination of a rotary cutter, a shaft, a carrier slidable on the shaft and having thereon positioning surfaces for the tread face of the shoe, a gage on the shaft for locating the heel breast of the shoe, and means for moving the carrier away from the gage and toward the cutter.

16. In a machine of the class described, the combination of a rotary cutter, a shaft, a carrier slidable longitudinally of the shaft,

17. the carrier having surfaces to engage the tread faces of the heel and forepart of the shoe to determine the orientation of the shoe in its longitudinal median plane, a gage on the shaft for locating the shoe lengthwise, means for holding the shoe so located, and means for moving the carrier to present the shoe to the cutter.

18. In a machine of the class described, the combination of a cutter for operating on the heel of a shoe, means arranged to be engaged by the breast of the heel to position the latter in a certain relation to the cutter before the heel is presented to the cutter, and

means arranged to transfer the heel from said positioning means to the cutter and to maintain said relation while the cutter is operating on the heel.

19. In a machine of the class described, the combination of a cutter for operating on a shoe, a gage for locating the shoe in a certain relation to the cutter but out of contact therewith, and means for relatively shifting the shoe and the cutter into cooperative relation and at the same time relatively shifting the shoe and said gage to separate them before the shoe and said cutter touch each other.

20. In a machine of the class described, the combination of a cutter for operating on a shoe, movable means including a tread rest for presenting the shoe to said cutter, and a gage arranged to locate the shoe relatively to said means before the latter is moved to present the shoe to the cutter, said gage and said cutter being so related that the shoe must be separated from the gage to undergo operation by said cutter.

In testimony whereof I have signed my name to this specification.

ALGERNON W. MATTHEWS.
